UNITED STATES PATENT OFFICE.

WILLIAM T. EMMES, OF CINCINNATI, OHIO.

CHANGE-SPEED MECHANISM FOR MACHINE TOOLS.

Application filed April 16, 1924. Serial No. 707,004.

This invention has for an object to produce a change speed device which is particularly designed for lathe constructions, but which may be as readily embodied in the construction of milling machines, boring machines or other machines and machine tools.

A further object is to produce a change speed mechanism in which relatively small, compact and simple parts are employed and in which these elements are so disposed relatively to one another, that they are readily accessible for purposes of repair, etc.

A further object is to produce a change speed mechanism in which a maximum number of speed changes are obtainable with a minimum number of parts.

A further object is to produce a change speed mechanism in which a minimum number of operations are necessary to obtain a maximum number of speed changes.

These and other objects are attained in the change speed mechanism described in the following specification and illustrated in the accompanying drawings, in which:—

Fig. 1 is a plan view of my improved change speed construction, parts being shown in section and other parts in elevation for convenience of illustration.

Fig. 2 is an end elevation of the casing enclosing my improved change speed mechanism.

Fig. 3 is a transverse sectional view taken on the line 3—3 of Fig. 1.

Fig. 4 is a transverse sectional view taken on the line 4—4 of Fig. 1.

Fig. 5 is a longitudinal sectional view of the portion of the mechanism designated by line 5—5 in Fig. 1.

Fig. 6 is a view of a direction chart or table which is employed in directing the operator of the machine tool as to the correct manner in manipulating the handles which control the shifting of the gears to obtain the various speed changes to be obtained by my improved mechanism.

Figs. 7 to 18 inclusive disclose in diagrammatic manner the positions of the gears, clutches and other objects of the mechanism, relatively to one another, in order to produce the several speed changes which are obtainable by means of my improved construction.

In my improved change speed mechanism I have disclosed, in Fig. 1, a casing 27 which

encloses all the elements of the speed change portion of my invention. Within the casing suitable bearings mount a drive shaft 28, a work-carrying spindle 29, a primary intermediate shaft 30 and a secondary intermediate shaft 31. Rotatively mounted upon shaft 28 are two pinions 32 and 33, pinion 32 being of smaller diameter than pinion 33. These two pinions are spaced apart and have located between them a clutch member 34 which is splined upon shaft 28. Teeth 35 and 36 upon pinion 32 and member 34 respectively, are adapted to engage when clutch member 34 is shifted toward pinion 32. Teeth 37 and 38 are formed upon member 34 and pinion 33 respectively and are adapted to engage when member 34 is moved toward pinion 33. Thus either pinion 32 or pinion 33 may be driven from clutch member 34 because of its splined connection with drive shaft 28.

Primary intermediate shaft 30 carries two gears 39 and 40 which are keyed thereto and which mesh continuously with pinions 32 and 33 respectively. Between gears 39 and 40 are a gear 41 and a pinion 42. This gear and pinion are rotatably mounted independently upon shaft 30. Gears 39 and 41 are provided with the respective clutch teeth 43 and 44 which are adapted to engage upon movement of gear 41 toward gear 39. Gear 40 and pinion 42 are provided with the respective clutch teeth 45 and 46 which will engage when pinion 42 is moved toward gear 40. Although gear 41 and pinion 42 are independent of each other, it is necessary that they be moved longitudinally of shaft 30 simultaneously, in order that clutch teeth 43—44 and clutch teeth 45—46 will not be engaged simultaneously.

To accomplish this I have provided a sliding bar 47, (see Figure 5) which is provided with embracing yoke 48. In order to limit the movement of this bar 47 I have provided a pin 49 which slides in a slot 50 in the mounting frame 51 which carries bar 47. This pin 49 extends above frame 51 in order that the bar may be operated from suitable instrumentality which will be described herein-after. Adjacent to bar 47 I have provided another bar 52, (see Fig. 4,) which is mounted in the same manner as bar 47 and which is provided with a pin 53, (see Fig. 1,) for causing reciprocation in the same manner as bar 47. This bar 52 is provided with a finger 54, (see Fig. 4,) which grasps

a flange 55 on clutch member 34, so that the clutch member may be reciprocated. As with pin 49, suitable instrumentalities which will also be described hereinafter, have been provided for effecting reciprocation of bar 52 in cooperation with its operating pin 53.

Work-carrying spindle 29, (see Fig. 1,) which lies next adjacent to shaft 30, carries a pinion 56 which is rotatably mounted on the spindle and which is provided with an elongated hub 57 having clutch teeth 58 at its end. Keyed to hub 57 are the united pinion 59 and gear 60, these meshing with gear 41 and pinion 42 respectively. Adjacent to teeth 58 is a clutch member 61 which is splined to spindle 29 and which carries clutch teeth 62 at one end for cooperation with teeth 58, teeth 63 being formed at the opposite end for cooperation with teeth 64 upon a gear 65 which is rotatably mounted on the spindle. Thus when clutch member 61 is moved either to the right or to the left, it will engage its teeth 63 and 62 with the cooperating teeth 64 and 58 respectively, so that the spindle will be driven either from gear 65 or pinion 56 as will be hereinafter more fully described. The manner and means of operation of clutch member 61 will also be described hereinafter.

Secondary intermediate shaft 31, which lies next adjacent to spindle 29, carries a rotatably mounted gear 66 which meshes continuously with pinion 56 on spindle 29. In addition to this another mounted gear 67 is provided. This gear meshes with gear 60 on hub 57 carried by spindle 29. Between gears 66 and 67 a clutch member 68, which is splined to shaft 31, is located. This member 68 is provided with clutch teeth 69 and 70, these teeth engaging the respective teeth 71 and 72 formed on the respective gears 66 and 67. Thus when member 68 is shifted to either of its extreme positions it will unite either of the gears 66 or 67 with shaft 31 for driving purposes. Adjacent to the opposite end of shaft 31 I have provided a pinion 73 which is keyed to the shaft and which meshes continuously with gear 65.

I will now describe the means by which the shifting of clutch members 34, 61, and 68, as well as of gear 41 and pinion 42, is accomplished. Engaging pin 53 is a lever 74, (see Fig. 3,) the hub 75 of which extends through casing 27 and has attached thereto an operating handle B, (see Fig. 2,) engaging pin 49 is a lever 76, (see Fig. 3,) the shaft 77 of which passes thru hub 75 and has attached thereto an operating lever A, (see Fig. 2.). In order to operate clutch member 68, (see Fig. 1,) I have provided a finger 78 which engages an annular groove 79 in the clutch member. The finger 78 is mounted in a short lever 80, (see Fig. 4,) attached to a shaft 81 extending through

the side of a casing 27 and to the outer end of which an operating lever D is attached. This lever when shifted to the right and then to the left, will bring clutch teeth 72-70, (see Fig. 1,) and 71-69 into alternate engagement. For retaining lever D, in either position designed to accomplish this, I have provided a ball and socket lever retaining device 82, (see Fig. 4.) The means for shifting clutch member 61 is identical with that for shifting member 68 and consists of a finger 83 which engages annular groove 84 of member 61, finger 83 being mounted upon lever 85, (see Fig. 3,) which is attached to shaft 86 which extends through casing 27 and is provided at its outer end with an operating lever C, (see Fig. 2.) Like lever D, lever C, is provided with a ball and socket lever retaining device 87, (see Fig. 3,) in order that member 61, when the lever C, is moved to one or the other of its positions, may retain teeth 58-62 or 63-64 in engagement. I have provided bars 47 and 52 with a ball and socket bar retaining device 88, (see Fig. 5,) which, like devices 82 and 87, operates to retain clutch member 34, (see Fig. 1,) in either of its shifted positions or to retain gear 41 and pinion 42 in either of their shifting positions. In each of these ball and socket devices 82, 87 and 88, the levers A, B, C, and D, are arranged for retention in neutral position, so that, the clutch teeth of none of their connected elements will engage. By this means and the shifting of the various clutches into one or the other of their several operative positions, the several speed changes, which I have indicated in Fig. 6, and which will be described hereinafter, will be accomplished.

The manner in which the several speed changes to be obtained by the mechanism I have disclosed in Fig. 1, is accomplished, will now be described, reference being had to Figs. 7 to 18 inclusive during such description, each of the figures showing how the shifting of the clutch members will accomplish the several speed changes indicated and shown in the direction table disclosed in Fig. 6 thereof. I have chosen to start my description with Fig. 7 in which elements of the mechanism are shown in the position they will occupy to produce a spindle speed of nine revolutions a minute. To produce this, spindle clutch member 34 is shifted so that teeth 35 and 36 will engage. By this means pinion 32, gear 39 and shaft 30 are rotated. Pinion 42 is shifted to bring teeth 45 and 46 into engagement and thus to drive pinion 42 and its gear 60 which also drives pinion 56. Shaft 31 is then operatively connected with gear 66 by shifting clutch member 68 so that teeth 69 and 71 will engage. Thus shaft 31 will drive pinion 73 and its cooperating gear 65. Spindle 29 is now

connected with gear 65 by moving clutch member 61 so that teeth 63 and 64 will engage. This will be accomplished by moving handles A, B, C, and D, to the left, 5 right, right and left respectively as indicated in the direction table of Fig. 6, and when standing in front of the operating front of a machine, which is the left hand side of Figs. 2, 3, and 4.

10 The next speed change to a spindle speed of 13 revolutions to the minute, Fig. 8, will be accomplished by shifting clutch member 34 to the right, so that teeth 37 and 38 engage. Pinion 42 is then shifted to the right, 15 so that teeth 45 and 46 engage. Clutch member 68 is also shifted, so that teeth 69 and 71 engage. Clutch member 61 is then shifted, so that teeth 63 and 64 engage. Thus the only difference between the setting 20 to produce 13 revolutions per minute as distinguished from 9 revolutions per minute, is in the position of clutch member 34 which is just the reverse of that previously described.

25 In Fig. 9, I have shown the setting required to produce a spindle speed of 18 revolutions per minute. This is accomplished by the mere shifting of clutch member 34 to bring teeth 35 and 36 into engagement and 30 by merely shifting gear 41 and pinion 42 so that teeth 45 and 46 are disengaged and teeth 43 and 44 are brought into engagement with each other. The clutch members 61 and 68 are allowed to remain in the positions 35 they occupied during the two speed changes previously described.

30 In Fig. 10, I have shown the setting required to produce a spindle speed of 24 revolutions per minute. This setting is identical with that shown in Fig. 9 except for the shifting of member 34 to bring teeth 37 and 38 into engagement.

45 In bringing about a spindle speed of 30 revolutions a minute, Fig. 11, clutch members 34 and 68 are now shifted to engage teeth 35 and 36, as well as teeth 70 and 72, gear 41 and pinion 42 being shifted to bring teeth 45 and 46 into engagement.

50 In Fig. 12, a spindle speed of 43 revolutions a minute is brought about, by merely shifting clutch member 34, from its position disclosed in Fig. 11, so that, teeth 37 and 38 are brought into engagement. The remaining shiftable members are allowed to 55 remain in the positions they occupy in producing the spindle speed of 30 revolutions per minute.

60 In Fig. 13, a speed of 60 revolutions per minute, will be imparted to the spindle, by merely shifting clutch member 34 and gear 41 with pinion 42. This change, from that disclosed in Fig. 12, brings teeth 35 and 36 as well as teeth 43 and 44 into engagement.

65 In Fig. 14, by now merely shifting clutch member 34, to bring teeth 37 and 38 into

engagement, I accomplish a change in spindle speed from 60 to 85 revolutions a minute.

Fig. 15, discloses the positions occupied by the shiftable member in order to produce a spindle speed of 125 revolutions a minute. This is accomplished by now shifting member 34 to bring teeth 35 and 36 into engagement, by shifting gear 41 and pinion 42 to bring teeth 45 and 46 into engagement, by 75 shifting clutch member 61, to bring teeth 58 and 62 into engagement and by shifting clutch member 68 to free both gears 66 and 67. Thus the spindle is driven directly from pinion 42, driving thru gear 60 and 80 splined clutch member 61 onto the spindle.

The next step-up in speed change is to 175 revolutions a minute, Fig. 16, and is accomplished, by merely shifting clutch member 34 from the position shown in Fig. 15, so 85 that teeth 37 and 38 will engage.

In Fig. 17, the shifting of clutch member 34 and gear 41 with pinion 42 in order that teeth 35-36 and teeth 43-44 may be engaged, will accomplish a speed change in 90 which the spindle is driven at 250 revolutions a minute.

In Fig. 18, the final increase in speed transmitted to the spindle, is accomplished by merely shifting member 34, so that its 95 teeth 37 and 38 engage. This speed is 350 revolutions a minute.

Having thus described my invention what I claim is:

1. A change speed mechanism comprising 100 a drive shaft, a primary intermediate shaft, a secondary intermediate shaft, a work spindle, and a series of constantly meshing gears on the shafts and spindle, the gears on the primary intermediate shaft consisting of a 105 pair of gears spaced apart and keyed to the shaft, and a pair of gears mounted on the shaft and having longitudinal shifting movement and independent rotation thereon, each of said keyed gears having clutch teeth on the sides thereof facing the rotatively mounted gears, each of said rotatively mounted gears having clutch teeth on the side thereof adjacent to and for cooperation with the clutch teeth of the keyed gears, and 110 a yoke embracing the faces of the independently rotatable gears, adapted to effect longitudinal movement of the rotatively mounted gears as a unit toward or away from one or the other of the keyed gears, 115 whereby engagement or disengagement of the sets of clutch teeth may be brought about, the gears on the drive shaft constantly meshing with the keyed gears on the primary intermediate shaft, and certain of the 120 gears on the spindle constantly meshing with the longitudinally shiftable independently rotatable gears of the primary intermediate shaft.

2. A change speed mechanism comprising 130

a drive shaft, a primary intermediate shaft, a secondary intermediate shaft, a work spindle, and a series of constantly meshing gears on the shafts and spindle, the gears on the 5 primary intermediate shaft consisting of a pair of gears spaced apart and keyed to the shaft, and a pair of gears mounted on the shaft and having longitudinal shifting movement and independent rotation thereon, 10 each of said keyed gears having clutch teeth on the side thereof facing the rotatively mounted gears, each of said rotatively mounted gears having clutch teeth on the side thereof adjacent to and for cooperation with the clutch teeth of the keyed gears, 15 and a yoke embracing the faces of the independently rotatable gears, adapted to effect longitudinal movement of the rotatively mounted gears as a unit toward or away from one or the other of the keyed gears, 20 whereby engagement or disengagement of the sets of clutch teeth may be brought about, the gears on the drive shaft constantly meshing with the keyed gears on the primary intermediate shaft, and certain of the gears on the spindle constantly meshing with the longitudinally shiftable independently rotatable gears of the primary intermediate shaft, the gears of each intermeshing pair of gears being of a different speed ratio than 25 any other of said pairs of intermeshing gears. 30

In witness whereof, I affix my signature.

WILLIAM T. EMMES.
